UNITED STATES PATENT OFFICE.

WILLIAM C. RUST, OF GOLDDALE, WASHINGTON.

COMB-HOLDER AND CLIP THEREFOR.

1,257,937.

Specification of Letters Patent. Patented Feb. 26, 1918.

Application filed May 16, 1917. Serial No. 169,003.

To all whom it may concern:

Be it known that I, WILLIAM C. RUST, a citizen of the United States, residing at Goldendale, in the county of Klickitat and State of Washington, have invented certain new and useful Improvements in Comb-Holders and Clips Therefor, of which the following is a specification, reference being had to the accompanying drawings.

10 This invention relates to means for retaining articles within a pocket, and particularly to means for holding a pocket comb.

The general object of this invention is to provide a simple and inexpensive comb clip and comb holder for pocket combs, so constructed as to prevent the comb from falling from the pocket when the wearer is in a stooping position, or otherwise actually engaged.

20 A further object is to so construct the clip that it may be used for combs of different sizes and for pockets of different depths.

And a further object is to provide a holder for the comb in which the comb may be inserted, this holder being constructed so as to provide for the projection of the clip into the pocket.

Other objects will appear in the course of the following description.

30 My invention is illustrated in the accompanying drawings, wherein:—

Figure 1 is a perspective view of my comb holder;

Fig. 2 is a longitudinal sectional view of the holder shown in Fig. 1, with the comb contained therein;

Fig. 3 is a side elevation of a comb with my improved clip applied thereto;

Fig. 4 is a section on the line 4—4 of Fig. 3;

Fig. 5 is a perspective view of a modified form of clip.

Referring to these drawings, 10 designates a comb of any suitable character having a back 11. Detachably engaged with the back is a clip 12, which is preferably formed of resilient metal, the body of the clip being bent over so that it is U-shaped in cross section to provide opposed jaws 13, which will

bind upon the back of the comb, the comb being preferably provided with a groove 14 extending longitudinally of the back adjacent the bases of the teeth with which the edges of the jaws engage. I do not wish to be limited to this, however. The body of 55 the clip 12 upon one face is formed with a longitudinally extending resilient tongue 15 terminating in a ball 16 or other rounded terminal end. This finger or tongue 15 is curved slightly inward. While it is preferable that the tongue 15 shall be formed integral with the clip, in the manner illustrated in Fig. 3 yet it is obvious that the tongue may be attached as by riveting or soldering one face of the clip, as illustrated in Fig. 5. 65 The clip may be ornamented in any suitable or desired manner, as may the tongue.

For the purpose of housing the comb with in the pocket, I may provide a holder 17 of leather or any other suitable material held 70 in shape by the binding 18, this holder having an opening at one end into which the comb may be inserted and being formed with a slit 19 through which the tongue 15 may be caused to project. When so projected, the clip will retain the holder on the comb and will retain the holder and comb both in the pocket.

It will be obvious that I do not wish to be limited to the exact form of the clip, comb or holder illustrated, as these may be made in various forms without departing from the spirit of my invention.

Having described my invention, what I claim is:—

1. The combination with a comb having longitudinally extending grooves on opposite faces of its back, of a U-shaped resilient clip providing jaws, the edges of which engage said grooves, one jaw of the clip being 90 provided with a longitudinally extending resilient tongue.

2. The combination with a comb and a clip mounted upon the back thereof and having a tongue extending longitudinally of 95 the comb and in a plane approximately parallel to one side face of the comb, of a sheath or holder for the comb, one side of which is

slotted for the projection of the tongue on said clip.

3. The combination with an article and a clip mounted upon the article and having a tongue extending longitudinally thereof, of a sheath or holder for the article having an opening at one end into which the article may be inserted, one side of the sheath being

slotted for the projection of the tongue of said clip.

In testimony whereof I hereunto affix my signature in the presence of two witnesses.

WILLIAM C. RUST.

Witnesses:

F. L. BRIDGEFARNON,
O. C. NELSON.
